UNITED STATES PATENT OFFICE.

PEDER T. MOLLER, OF SEATTLE, WASHINGTON.

CORK-EXTRACTOR.

1,113,465.

Specification of Letters Patent. Patented Oct. 13, 1914.

Application filed January 13, 1914. Serial No. 811,889.

To all whom it may concern:

Be it known that I, PEDER T. MOLLER, citizen of the United States, residing at Seattle, in the county of King and State of

5 Washington, have invented certain new and useful Improvements in Cork-Extractors, of which the following is a specification, reference being had to the accompanying drawings.

10 This invention relates to cork extractors and has for one of its primary objects to provide a simple, efficient and reliable device of this character capable of quick and easy engagement with the cork to extract the same 15 from the neck of a bottle, without in any way injuring the cork in such manner as to preclude its further use.

The invention has for another and more specific object to provide a cork extractor 20 including a hollow shank, an extensible bracket mounted upon said shank and adapted to be received within the same, said shank having a pointed terminal whereby the same may be readily forced into the neck of a 25 bottle between the same and the cork, and means for extending said bracket beneath the inner end of the cork whereby the same is removed from the bottle neck when the shank is pulled outwardly.

30 The invention has for a more particular object to provide an extensible bracket consisting of two hingedly connected sections, one of said sections being mounted within one end of the hollow shank, and the other 35 section of the bracket being slidably engaged at one end in the shank, and means connected to the latter bracket section and manually movable in the shank of the extractor whereby said bracket sections may be disposed in 40 longitudinal alinement and wholly arranged within the shank, or projected therefrom.

The invention has for another of its objects to produce a device of the above character which may be inexpensively manufactured, is very strong and durable in practical use, and provides means whereby the extraction of corks is greatly facilitated.

With the above and other objects in view as will become apparent as the description

proceeds, the invention consists in certain 50 constructions, combinations and arrangements of the parts that I shall hereinafter fully describe and claim.

For a full understanding of the invention, reference is to be had to the following 55 description and accompanying drawing, in which—

Figure 1 is a side elevation of my improved extractor, partly in section, showing the same arranged in operative position in a 60 bottle neck. Fig. 2 is an elevation of the extractor, the bracket sections being disposed within the hollow shank. Fig. 3 is a section taken on the line 3—3 of Fig. 1. Fig. 4 is a section taken on the line 4—4 of Fig. 2. 65

Referring in detail to the drawing, 5 designates the metal shank of my improved extracting tool which is of hollow construction and preferably of substantially oval-shape in cross section as clearly shown in Fig. 3. The 70 upper end of this shank is provided with a suitable handle 6 while the lower end thereof terminates in a flattened point or spur 7. The hollow shank 5 is provided in its lower portion with a longitudinal slot 8 for a purpose which will more fully appear in the following description, and the upper end of the shank 5 adjacent to the handle 6 also has a slot 9 cut therein. A rod 10 is loosely 75 mounted for longitudinal movement in the hollow shank and at its upper end a finger piece 11 is loosely connected thereto. This finger piece extends outwardly through the slot 9.

12 indicates one leg of a bracket which is 80 pivotally mounted at one of its ends as indicated at 13 in the lower end of the hollow shank 5. To the other end of the leg 12, the second bracket leg 14 is pivotally connected. The other end of this latter leg is provided 85 with oppositely projecting lugs 15 for movement in grooves 16 formed in the inner wall of the shank 5. To this latter end of the bracket leg 14, the lower end of the rod 10 is pivotally connected. A coil spring 17 is 90 arranged in the upper end of the shank 5 and bears against the finger piece 11, said spring normally acting to force the rod 10 95

downwardly and extend the cork engaging bracket to the position shown in Fig. 1, wherein it will be noted that the leg 14 extends horizontally beneath the inner end of the cork while the leg 12 is obliquely disposed. A leaf spring 18 is fixed at one of its ends to the inner wall of the shank 5 and bears against the bracket leg 12, said spring normally acting to force the same outwardly 10 through the slot 8.

When the device is not in use, the bracket legs 12 and 14 are disposed in longitudinal alinement within the hollow shank 5 as shown in Fig. 2, and are adapted to be retained in this position against the action of the springs 17 and 18 by simply turning the finger piece 11 upon the upper end of the rod 10 into a notch 19 provided in the wall of the shank 5 at one side of the slot 9.

From the above description taken in connection with the accompanying drawing, the manner of operating the device will be obvious. The extensible bracket being disposed within the hollow shank 5, as shown in Fig. 2, the operator engages the spur or pointed lower end 7 of the shank 5 between the neck of the bottle and the cork and forces the shank downwardly into the bottle neck. Owing to the oval cross sectional form of the shank, the frictional resistance offered by the cork to this movement is minimized. When the shank has been forced inwardly into the bottle neck to a sufficient extent, the operator releases the finger piece 11 from the notch 19 so that the spring 17 will act to force the rod 10 downwardly, while the spring 18 at the same time exerts an outward pressure against the bracket leg 12, thus disposing the bracket legs 12 and 14 in the relative positions shown in Fig. 1. The operator now grasps the handle 6 and pulls outwardly upon the extractor so that the horizontal bracket leg 14 bearing against the inner end of the cork withdraws or extracts the same from the neck of the bottle. In this manner, it will be appreciated that the cork may be very easily and quickly removed from the bottle neck without mutilation or injury thereto.

When the device is not in use, the legs of the bracket being disposed entirely within the hollow shank 5 are protected against possible distortion or injury which would preclude their proper movement into or out of said shank.

The device as a whole is extremely simple in its construction, may be readily manipulated without necessitating any undue exertion and is extremely convenient and serviceable in practical use.

While I have above described and shown the preferred construction and arrangement of the several elements employed, it will be understood that the invention is susceptible

of a great many minor modifications therein 65 and I therefore reserve the right of resorting to all such legitimate changes as may be fairly embodied within the spirit and scope of the invention as claimed.

Having thus described the invention, what 70 is claimed is:

1. A cork extractor comprising a shank adapted to be inserted between the neck of a bottle and the cork, a bracket consisting of two sections pivotally connected together, 75 one of said sections being pivotally mounted upon the shank and the other having a slideable connection therewith, and movable means carried by the shank and connected to said latter bracket section to extend said 80 bracket sections to their effective positions whereby the cork is removed from the bottle neck when the shank is extracted.

2. A cork extractor comprising a hollow shank adapted for insertion between the 85 neck of a bottle and the cork, a bracket consisting of two sections pivotally connected together, one of said sections being pivotally mounted upon the shank, the other bracket section being slidably mounted in 90 the bore of the shank, said bracket sections being adapted to be disposed in longitudinal alinement and entirely within the hollow shank, and a rod slidably mounted in the shank and connected to said latter bracket 95 section whereby the bracket may be extended laterally from the shank beneath the cork and the cork removed when the shank is extracted from the bottle neck.

3. A cork extractor comprising a hollow 100 shank adapted for insertion between the neck of a bottle and the cork, the wall of said shank having a longitudinal slot at one end, a bracket comprising two sections pivotally connected together, one of said sections being pivotally mounted in the bore of the shank and the other section being slidably mounted in said bore, said bracket sections being adapted to be disposed in longitudinal alinement within the bore of 105 the shank, a spring arranged in the shank bore and bearing against the first named bracket section to force the same outwardly 110 through said slot, and a longitudinally movable rod arranged within the bore of the 115 shank and connected to said latter bracket section whereby said bracket may be extended laterally from the shank beneath the cork and the cork removed from the bottle neck when the shank is extracted.

4. A cork extractor comprising a hollow shank adapted for insertion between the neck of a bottle and the cork, the wall of said shank being provided with a slot at one end, relatively movable bracket sections, 125 one of said sections being pivotally mounted in the bore of the shank, a longitudinally movable rod in said shank connected to the

other bracket section, a finger piece loosely connected to said rod, said shank being provided with an additional slot through which said finger piece extends and a notch in one edge of said slot, and a spring arranged in the shank and bearing against the finger piece to move said rod and normally dispose the bracket sections in their extended positions, said finger piece when the rod is retracted against the action of the spring

being adapted for engagement in said notch to retain the bracket sections in longitudinal alignment within the bore of the shank.

In testimony whereof I hereunto affix my signature in the presence of two witnesses. 15

PEDER T. MOLLER.
